CLAIM

The ornamental design for a cover for earphone case, as shown and described.

DESCRIPTION

FIG. 1 is a front-upper-right perspective view of a cover for earphone case according to the present invention.

FIG. 2 is a front-lower-left perspective view of the cover for earphone case of FIG. 1.

FIG. 3 is a rear-upper-right perspective view of the cover for earphone case of FIG. 1.

FIG. 4 is a front view of the cover for earphone case of FIG. 1.

FIG. 5 is a rear view of the cover for earphone case of FIG. 1.

FIG. 6 is a left side view of the cover for earphone case of FIG. 1.

FIG. 7 is a right side view of the cover for earphone case of FIG. 1.

FIG. 8 is a top view of the cover for earphone case of FIG. 1.

FIG. 9 is a bottom view of the cover for earphone case of FIG. 1; and,

FIG. 10 is a front-upper-right perspective view of the cover for earphone case of FIG. 1, showing with a lid portion open. The features depicted in broken lines form no part of the claimed design.

1 Claim, 10 Drawing Sheets
